UNITED STATES PATENT OFFICE

164,584

DESK

Ervin C. Koegel, St. Louis, Mo.

Application January 6, 1951, Serial No. 13,690

Term of patent 14 years

(Cl. D33—7)

To all whom it may concern:

Be it known that I, Ervin C. Koegel, a citizen of the United States, residing in the city of St. Louis and State of Missouri, have invented a new, original, and ornamental Design for a Desk, of which the following is a specification, reference being had to the accompanying drawing, forming a part thereof.

In the drawing:

Fig. 1 is a perspective view showing the front and one end of the desk of my novel design;

Fig. 2 is a perspective view showing the back and one end of the desk;

Fig. 3 is a perspective view showing the back and the opposite end of the desk, and

Fig. 4 is a view similar to Fig. 1 on a somewhat reduced scale, of a desk embodying my novel design, and showing the detachable top element removed from the desk.

I claim:

The ornamental design for a desk, substantially as shown.

ERVIN C. KOEGEL.
